CLAIM

The ornamental design for a pipe adapter for water as shown and described.

DESCRIPTION

FIG. 1 is a perspective view of a pipe adapter for water showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 6; and,

FIG. 11 is an enlarged view of portion 11 shown in FIG. 7. The broken lines in the drawings depict portions of the pipe adapter for water that form no part of the claimed design. The dot-dash broken lines surrounding details shown in FIGS. 1, 6-7, and 9-11 are for the purpose of annotating the enlarged view only and form no part of the claimed design.
